ASH GATE

Filed March 30, 1926

UNITED STATES PATENT OFFICE.

GERALD J. OLDRYD, OF PHILADELPHIA, PENNSYLVANIA, ASSIGNOR TO LINK-BELT COMPANY, OF CHICAGO, ILLINOIS, A CORPORATION OF ILLINOIS.

ASH GATE.

Application filed March 30, 1926. Serial No. 98,570.

My invention relates to certain improvements in ash-gates used in discharging ashes from the hoppers of stoker fired boilers, but it will be understood that the invention can 5 be used in any type of ash-hopper as desired.

Water is used to quench the ashes in the ash-hopper to hasten cooling, and as more water is used than the ashes absorb, there is a certain amount of water that should be 10 carried away and not allowed to escape into the car or other conveying medium.

Furthermore, a certain amount of fines or silt will pass through the gate with the water, and this silt clogs the water-trough 15 unless it is removed.

An object of my invention, therefore, is to provide means for carrying off the excess water from the gate, and to provide means for discharging the fines or silt that collects 20 in the drip-trough.

In the accompanying drawing:

Fig. 1 is a sectional elevation of a portion of an ash-hopper illustrating my improved ash-gate;

25 Fig. 2 is a face view of the gate;

Fig. 3 is a view similar to Fig. 1, but showing the gate in section and in open position; and

Fig. 4 is an enlarged sectional view of the 30 trough showing the scraper in position.

The ash-hopper 1 has an inclined bottom, and in the bottom is an opening 2. This opening is closed by a gate structure 3. Below the gate structure are tracks 4 for cars 5 shown by dotted lines in Fig. 1. While I have illustrated a track and cars as a conveying medium, any suitable type of conveyor may be used in place of the cars for carrying away the ashes as they are discharged from the hopper.

The frame 6 of the ash-gate is securely attached to the underside of the hopper as shown in Fig. 1, and pivoted at 7 to the frame is a chop-gate 8, which, when raised as 45 shown in Fig. 3, allows the ashes to flow from the hopper into the car or other conveyor located directly below the gate.

The gate has a curved body portion 9 and sides 10. Trunnions 7, which form the pivots, extend through bearings 11 in the frame 6, and have at their outer ends arms 12 on

which are adjustable weights 13. Hung to one or both of these arms is a handled operating rod 14. On pulling this rod down, the gate can be opened to any extent desired and 55 can be held in this position until the car has been loaded, and on releasing, the gate can be closed.

At each side of the body portion 6 of the gate are brackets 15, having bearings for 60 the trunnions 16 of the water drip-trough 17. This trough has an inclined bottom as shown in Fig. 2, and is closed at one end and has an opening 18 at the opposite end.

The open end of the trough extends over 65 one end of the drain 19, which has an inclined bottom and is provided with a discharge opening 20, so that any water passing from the trough into the drain will be discharged through the opening 20 into a gutter 70 21 or other suitable receptacle.

On the trunnions 16 of the trough 17 are arms 22, which are connected by links 23 to arms 24 on the trunnions 7 of the gate, so that as the gate is moved into the open position, the trough is turned to the discharge 75 position shown in Fig. 3.

Depending from the body 6 of the gate is a scraper 25, which is fixed in the present instance and extends to the bottom of the 80 water drip-trough. The bottom of the trough is rounded as shown so that as the trough is moved from the position shown in Fig. 1 to that shown in Fig. 3, any silt or fine material 85 will be scraped from the drip-trough and will be discharged into the car or other receptacle, so that the trough is kept comparatively free for the escape of water through the drain.

I claim:

1. The combination with a gate structure including a frame and a gate pivotally mounted in said frame, of a bracket carried by the said structure on each side of said gate, a drip-trough disposed beneath said gate, said trough having trunnions mounted in said brackets, said trough being inclined and having the lower end thereof open, a scraper extending from the frame into the said trough, the lower edge of the scraper being inclined to correspond to the inclined bottom of said trough, and means connect-

ing the gate and trough whereby said trough will be turned on its trunnions in unison with the turning of the gate on its axis.

2. The combination with a gate structure including a frame and a gate pivotally mounted in said frame, a flange depending from the frame and forming a scraper, a drip trough pivotally mounted beneath the

said flange and carried by the said structure independently of the gate, said scraper being disposed within said trough, and means connecting the gate and trough whereby said trough will be turned in unison with the turning of the gate on the axis. ¹⁰
